CAN-BEADING MACHINE

Wiltie I. Gladfelter, Philadelphia, Pa., and Walter A. Ehrlich, Bridgeport, Conn., assignors to Crown Can Company, Philadelphia, Pa., a corporation of Pennsylvania

Application June 22, 1943, Serial No. 491,836

12 Claims. (Cl. 153—73)

1

The present invention relates to an improved machine for impressing strengthening ribs or beads in the cylindrical surfaces of can bodies and the like. Such strengthening beads are conventionally employed in can bodies to prevent denting or collapse thereof and to make possible the use of lighter sheet metal stock than would otherwise be possible. In order to decrease the thickness of the sheet metal employed in the manufacture of can bodies, attempts have been made to form the strengthening beads of maximum depth, thereby to compensate for the strength and stiffness ordinarily imparted to the bodies by heavier stock.

In accordance with conventional methods and machines, prior to the present invention, strengthening beads have been formed in the cylindrical side walls of can bodies by the use of can body supporting mandrels having peripheral grooves formed therein, and cooperating can body beading rolls positioned exteriorly of the can bodies and having supplemental ribs thereon. In these machines, the bodies are rolled between the mandrels and the beading rolls, and the beads thereby impressed. An example of a machine of the prior art is shown in the patent to Kreuger 2,081,042. In such machines, the can bodies are subjected to the action of instrumentalities of this type and the strengthening beads are formed therein by cooperating ribs and grooves on the surfaces of the beading rolls and can supporting mandrels, respectively. The rolling force is transmitted from the can supporting mandrel, through the can body thereon, to the exteriorly positioned beading roll, by means of a plurality of rubber rings interspersed between the bead forming or die rings of hardened metal.

When attempts are made with machines of the type heretofore used, to increase the depth of the strengthening beads, a limit of depth is soon reached, beyond which the beads cannot be formed, because of a failure of the rubber rings to transmit rotational forces from the inner can supporting mandrels to the exteriorly positioned beading rolls, particularly at the side seams of the can bodies where four thicknesses of metal must pass through the bight between the mandrels and rolls and between the beading rings. It has been found, in practice that when attempts are made to form deep beads in can bodies, the side seams will not pass between the mandrels and the rolls, but, on the contrary the mandrels will slip and will fail to rotate the can bodies and the beading rolls when the side seams are encountered.

2

The present invention has for its purpose to overcome all of the difficulties encountered with machines of the prior art.

A primary object of the invention is to provide a machine capable of forming in the side walls of can bodies, reinforcing ribs, grooves or beads of greater depth and uniformity than has been possible heretofore.

A further object is to provide means for preventing slippage between the inner and outer beading rolls of can beading machines, or, in other words, between the can supporting mandrels, the can bodies and the beading rolls.

Another object is to provide means which will make it possible to apply greater beading pressure to the can bodies, yet which will facilitate passage of the side seams through the bight between the mandrels and the beading rolls.

A further object is to provide means for supporting the free ends of the internal beading rolls or can supporting mandrels, to the end that they may withstand greater beading pressure applied thereto by the external beading rolls.

Still another object is to provide an improved means for rotating the can body supporting mandrels and, in combination therewith, to provide improved means for imparting positive rotation to the beading rolls, irrespective of their radial positions relative to the mandrels.

Other and further objects and advantages of the invention will be apparent to persons skilled in the art, from a consideration of the specific embodiment of the invention shown in the accompanying drawings, in which:

Figure 1 is a side elevation of the apparatus.
Figure 2 is a vertical longitudinal section.

Figure 3 is a vertical transverse section taken substantially on line 3—3 of Figures 1 and 2.

Figure 4 is a similar section taken on line 4—4 of Figures 1 and 2.

Figure 5 is a similar section taken on line 5—5 of Figures 1 and 2.

Figure 6 is an enlarged elevational view of a stationary cam for imparting radial movement to the beading rolls.

Figure 7 is an enlarged detail view of a preferred form of gear train interconnecting the outer and inner beading rolls.

Figure 8 is a fragmentary section showing certain details of the rolls and their supporting means.

Figure 9 is a fragmentary plan view of the gearing shown in Figure 7.

Figure 10 is an enlarged longitudinal section

showing a portion of the turret and one pair of beading rolls.

Figure 11 is a detail section and plan, illustrating the cam follower associated with the cam of Figure 6.

Figure 12 is a detail section on line 12—12 of Figure 11, and

Figure 13 is a similar section on line 13—13 of Figure 11.

The apparatus is mounted upon a base 10 and includes end frame members 11, 12, projecting upwardly therefrom and serving to support a stationary horizontally disposed shaft 13. Upon the shaft there is a main turret 15 comprising spaced heads 16, 17 and a substantially cylindrical connecting rim 18, journalled on bearings 19 and 20. A cylindrical turret extension 21, connected to the head 17, projects laterally, coaxially with the shaft 13, toward the opposite end of the machine, where it is secured to a large spur gear 22, journalled on the shaft 13 upon bearings 23. The turret extension 21 comprises a cylindrical portion 24 of reduced diameter and another cylindrical portion 25 of large diameter connected thereto by a radial web 25' provided with a plurality of pairs of guiding bores 26, for the reception of can body carrying rods 27, 28, described in detail below. At the end adjacent its connection to the gear 22, the turret extension is provided with an inwardly projecting flange 29, similarly provided with bores 30 for supporting and guiding the rods 27, 28.

It will be noted that the turret 15, the turret extension 21 and the large spur gear 22 are all interconnected for rotation upon the stationary shaft 13 in unison. The shaft carries a cam barrel 35, secured against rotation by a key 36, and having a peripheral cam track or groove 37 formed therein, provided with an advanced section at its upper portion and a retracted section at its lower portion. Cam following rollers 38, carried by brackets 39, fast upon the pairs of rods 27, 28, are disposed in the cam track 37, to reciprocate the rods longitudinally, as the turret revolves about the shaft 13.

As indicated in Figures 4, 8 and 10, the slide rods 27, 28 carry can body end engaging plates 40, 41 and side wall engaging elements 42, 43, adapted to advance the can bodies from an infeed position onto the associated beading mandrel, into a beading position and to retract the same therefrom as the rods approach a discharge position. In other words, the rods 27, 28 and the can body engaging members carried thereby, which reciprocate as the turret revolves, serve to move the cans to and from operative relation to the beading instrumentalities.

As indicated in Figure 4, an infeed star wheel or spider 45, fast on a shaft 46, is positioned adjacent the bottom of an infeed chute 47, down which the container bodies roll by gravity from the preceding machine in the line. The star wheel 45 is rotated in timed relation to the rotation of the turret, so that can bodies are fed into the spaces between the rods 27, 28, the end guide plates 40, 41 and the cradle members 42, 43, when the rods are in their retracted position, as shown at the bottom of Figure 2. As the cans move around with the can holders on the turret, and as they are advanced by the movement of the rods, they are supported by a curved, forwardly leading guide plate 48 until they have been placed upon and are supported by the beading mandrels, hereinafter described.

After the beading operation has been com-

pleted, the rods 27, 28 and the can engaging members carried thereby are retracted, as they approach a discharge chute 49, which receives the can bodies by gravity when they are stripped from the beading mandrels by this retraction. The chute 49 preferably comprises a pivoted section 50, connected by a spring-pressed link 51 to a limit switch 52, adapted to cut off the main driving motor in the event of a jam in the line of can bodies moving from the machine to the next machine in the line.

The head 16 of the turret (Figs. 2, 5 and 10) has a plurality of rearwardly projecting, arcuate flanges 53 formed integrally therewith and shaped to provide seats 54, for laterally projecting wings associated with caps 55 forming portions of rearwardly extending tubular sleeves 56. The sleeves 56 have bearing assemblies 57, 58 at their opposite ends, in which spindles 59 are journalled. Each spindle carries on its rear end a spur gear 60 and on its forward end a beading mandrel 61, composed of alternate rubber and steel rings 62, 63, the latter having beading grooves 64 formed in their peripheries. The mandrel is provided at its rear end with a hub 65 terminating in a spur gear 66, and at its forward end with a hub 67, screwed onto the spindle 59 and having a reduced portion 68 for the reception of a roller 69, held in place by an end cap 70, restrained against endwise movement by a screw 71 and against rotation by a dowel pin 72.

It will be apparent that, by this construction, the rings 62, 63 may be removed and others substituted, to accommodate can bodies of various sizes and to produce strengthening beads of various spacings and depths.

The turret heads 16 and 17 are provided with a plurality of radially disposed bores or slideways 75, 76, which receive supporting means for the beading rolls 77, positioned radially inwardly of the outer beading rolls or mandrels 61. As shown in Figures 7, 8 and 10, each beading roll support comprises a rack sleeve 78 slidably mounted in one of the bores or slideways 75, 76 and having laterally projecting rack teeth 79 formed thereon. At its upper end, the sleeve terminates in a platform 80 having recessed spring seats 81, 82 formed therein, for the reception of relatively heavy compression springs 83, 84, bearing upwardly against a bearing bracket 85 provided with a depending stem 86, slidably received in the bore of the sleeve 78 and having a nut 87, threaded on its projecting end, below the sleeve 78. The springs 83, 84 normally maintain the bearing bracket 85 in the upwardly projected position, as determined by the engagement of the nut 87 with the end of the sleeve 78, leaving a space 88 between the lower face of the bracket 85 and the upper surface of the platform 80. A cap 89, secured to the bracket by screw 90, secures the bearing assembly 91 thereto.

Each bearing assembly 91 (Figure 10) supports one end of a spindle or shaft 92 for the beading roll 77, made up of a plurality of alternate rubber and metallic rings 93, 94, the latter being provided with outwardly projecting beading ribs 95, positioned in alignment with the beading grooves 64 on the outer beading roll or mandrel 61.

At the rear end, each roll shaft 92 carries a gear 96 of slightly smaller diameter than the beading roll.

For purposes hereinafter explained, the diameters of the gears 66 and 96 are of the same relative proportion as the diameters of the beading rolls 61 and 93.

The heads 16, 17 of the turret also carry a plurality of rock shafts 100, journalled in appropriate apertures therein and provided with teeth 101 in mesh with the rack teeth 97. Each shaft 100 carries, on its rear end, a crank arm 102, having a roller 103 journalled on a stud 104 and disposed in a cam groove 105 formed in a cam plate 106, carried by the shaft 13 and restrained against rotation by a key 107. As shown in Figures 11 and 12, the angular relation between the crank 102 and the rock shaft 100 may be adjusted by means of a worm screw 108 mounted in a bore 109 in the crank and having its threads disposed in engagement with peripheral teeth 110 formed on the shaft 100. Rotation of the screw 108 imparts rotational adjustment to the rock shaft 100, after the manner of a worm gear, and when the desired adjustment has been effected, the screw may be locked in position by a nut 111.

As shown in Figure 13, the cam following roller 103 is journalled upon the end of the stud 104, with a bushing 112 interposed, lubricant being provided by bores 113, and the stud being held in place by a pin 114.

By reference to Figures 5 and 6, it will be apparent that, as the cam following rollers 103 enter the radially outermost portion 105a of the cam track 105, the rock shafts 100 will be oscillated. This movement is transmitted by the pinion teeth 101 to the rack sleeves 78, to project the beading rolls 77 outwardly into beading engagement with can bodies on the mandrels 61. The lost motion connection between the bearing brackets and the platforms 80, provided by the spaces 88, permits the compression springs 83, 84, to yield when the side seams of the can bodies pass through the bight between the beading rolls. However, the springs 83, 84 are sufficiently powerful to apply a substantial beading force to the side seams, so that the latter are provided with strengthening beads, similar to the other portions of the can bodies. The use of heavy compression springs is desirable, since they make it possible to apply sufficient compression forces to form deep strengthening beads in the can bodies, yet they permit the rolls to separate when the side seams pass therebetween, thereby preventing slippage between the beading rolls and the can bodies.

The gears 60, fast upon the ends of the spindles 59, are all in mesh with an orbit gear 120 carried by a hub 121 journalled on the shaft 13 by bearings 122. The hub 121 also carries a gear 123 in mesh with a similar gear 124 fast upon a rotatable shaft 125 journalled in the frame 11 at one end by bearings 126 and in the frame 12 at the other end by bearings 127, an intermediate portion of the shaft being supported in bearings 128, carried by an upstanding portion 129 of the forward portion of the frame 12. The shaft 125 also carries a spur gear 130, held fast thereon by a key 131 and disposed in mesh with the main turret gear 22, whereby the turret is revolved. A motor 132 (Fig. 1) connected through a speed reducer 133 to a sprocket or pulley 134 drives the shaft 125 by a belt or chain trained about a sprocket or pulley 135 fast on the end of that shaft.

From a consideration of the above arrangement, it will be appreciated that the drive shaft 125 serves to rotate the turret and the turret extension by means of the gears 130 and 22 and that the orbit gear 120 rotates each of the mandrel supporting spindles 59 through its connection with the gears 60. The ratio between the gears 124, 123, 120 and 60 is such that the spindles are

rapidly rotated in the desired direction, at the desired speed. By changing the relative sizes of the gears 124 and 123, the speed of rotation of the orbit gear 120 and of the spindles may be varied at will.

An important feature of the machine of the present invention is the use of means for positively driving the radially movable inner beading rolls 77, from and at the same peripheral speeds as the outer beading rolls or can body supporting mandrels 61. A direct geared interconnection between these rolls is difficult, if not impossible, to employ, in view of the fact that the inner series of rolls are moved a substantial distance, radially with respect to the outer series of rolls, to permit the can bodies to be passed over the free ends of the outer rolls when cans are fed into and removed from beading position. It is difficult if not impossible to assure meshing of such gears, when the rolls are brought together. The present invention obviates this difficulty by providing an offset gear train, continuously in mesh with the gears 66 and 96 which permits radial movement of the spindle 92, without disengagement of the gear train.

Referring to Figures 7 and 9, the turret head 16 carries a plurality of plate-like brackets 140, secured thereto by screws 141 and having an offset portion 143 providing a recess for a nut 144, screwed upon a stud 145 extending through the plate and carrying a spur gear 146, in mesh with the gear 66. A similar gear 147, in mesh with the gear 146 and also with the gear 96, is journalled on a stud 148 carried by the lower portion of the outwardly projected offset portion 143 of the bracket 140. As indicated by dotted lines in Figures 7 and 8, lubricant for the gears 146, 147 is supplied by a bore 149 in the plate 140, leading through branch conduits 150 to conduits 151 in the studs.

It will be seen, by reference to Figure 7, that the gear 96, fast upon the spindle 92 and positioned to one side of the gear 147, is free to move radially of the turret a short distance, without becoming disengaged from the gear 147. Hence, the inner and outer beading rolls are continuously rotated at the same peripheral speed, regardless of the radial position of the inner roll 77.

As stated above, the inner beading rolls 77 are urged outwardly into beading relation to the can bodies 200 on the mandrels 61 with very substantial force, by means of the cam followers 103, cranks 102, rock shafts 100, and the rack and pinion devices heretofore described. One of the important features of the machine of the present invention is the provision of means for preventing displacement of the free ends of the mandrels 61 under the influence of the force so applied to them. It should be remembered that the ends of the mandrels must be free and unsupported throughout the lower portion of their path of travel, in order that container bodies may be placed thereon and removed therefrom by longitudinal movement relative thereto. This is not a serious objection, however, since throughout this portion of their revolution with the turret, no force is applied to the mandrels by the beading rolls, as indicated in the lower half of Figure 4.

Between the supporting frames 11 and 12, and mounted upon the base 10, there is an intermediate supporting frame 155, having upwardly projecting limbs 156, 157 disposed on opposite sides of the turret and terminating at their upper ends in seats 158, 159, upon which an overhanging arch member 160 is mounted. The arch has

a downwardly facing arcuate track surface 161, positioned to be engaged by the rollers 69 on the ends of the spindles 59, at the outer or free ends of the beading mandrels. The vertical position of the arch 160 and the arcuate track surface 161 may be accurately determined by the use of shims or the like on the seats 153, 159, in order that the track will be firmly engaged by the rollers on the mandrels as they revolve with the turret and rotate on their own axes. The arch effectively prevents any upward or outward displacement of the mandrels under the influence of the force applied thereto by the beading rolls. Hence, it is possible to apply to the can bodies 200 on the beading rolls considerably more pressure than in machines of similar design heretofore used.

It is thought that the operation of the machine of the present invention will be entirely clear to those skilled in the art from the foregoing description. The turret 15 and the turret extension 21 are rotated as a unit upon the stationary horizontal shaft 13 by the drive shaft 125, through gears 130 and 22. As the turret rotates, the rods 27, 28 and the can carriers secured thereto are reciprocated longitudinally, to place can bodies upon and to remove them from the mandrels 61, the can bodies being delivered to the carriers by the star wheel 45 and being conveyed away from the machine by the discharge chute 49.

After the can bodies have been placed upon the mandrels, during their travel from the infeed station *a* (Fig. 4) to the station *b*, the beading rolls 77 are moved radially outwardly into contact with the can bodies, as indicated at station *c*, displacement of the mandrels 61 being prevented by the arch 160.

During all of these movements, the beading mandrels and the beading rolls are positively rotated at the same peripheral speed as a result of their interconnection through gears 60, 146, 147 and 96. Gear 124 on the shaft 125 drives the spur gear 123 and the orbit gear 120, which in turn drives the gears 60 and the spindles 59. Hence, as the beading rolls and the can bodies pass from station *c* through stations *d* and *e*, the can bodies are rolled between the beading rolls and strengthening beads are formed therein. As the side seams of the can bodies pass between the rolls, the latter are permitted to separate somewhat, by the coil compression springs 83, 84.

Between stations *e* and *f* (Fig. 4), the inner beading rolls are moved radially inwardly by the cam following cranks and rock shafts, and the can strippers on the rods 27, 28 remove the can bodies from the mandrels, in order that they may drop from the machine into the discharge chute, substantially at the station *g*.

It must be understood that the invention is not limited to the details of construction and arrangement of parts included in the specific embodiment shown in the accompanying drawings and described above, since many modifications will occur to those skilled in the art from a consideration of this disclosure. All modifications coming within the scope of the appended claims and their equivalents are included in the invention.

We claim:

1. A can body beading machine comprising a rotatable turret, a plurality of pairs of parallel beading rolls carried by the turret and journalled for rotation on radially spaced axes, one roll of each pair being supported at one end only, for the reception of can bodies over its other end, a

gear fixed upon the other end of each roll, a pair of offset intermeshing idler gears carried by the turret adjacent each pair of roll gears in mesh therewith and constituting a driving connection therebetween, means for forcefully moving the other roll of each pair substantially radially of the turret toward the first mentioned roll to apply beading pressure to the can bodies thereon while maintaining said driving connection, means for positively rotating the first mentioned roll of each pair, and means adjacent the path of movement of the free end of the first mentioned roll of each pair for preventing displacement thereof under the influence of said beading pressure.

15 2. A can body beading machine comprising a rotatable turret, a circular series of beading rolls carried by the turret, a second series of beading rolls carried by the turret radially inwardly of the first series and disposed in parallel relation thereto, means for rotatably supporting the rolls of the outer series at one end only, whereby a can body may be passed over the unsupported end, 20 means for rotatably supporting the rolls of the inner series at both ends, means for forcefully moving the last-mentioned supporting means and the rolls carried thereby radially outwardly into beading relation to can bodies on the first-mentioned rolls, a plurality of gear trains permanently interconnecting each pair of inner and outer rolls, 25 means for positively rotating each outer roll, and means adjacent the path of movement of the free ends of the outer series of rolls for resisting the beading force applied thereto by the inner series of rolls and for preventing displacement thereof under said force.

3. A can body beading machine comprising a rotatable turret, a plurality of parallel beading roll spindles arranged in a circular series and journalled in the turret for rotation about their axes, a beading roll projecting from one end of each spindle and having a free end remote from the spindle journal, whereby can bodies may be passed thereover, a second set of beading rolls arranged in a circular series in parallel relation to the first-mentioned rolls, means for moving each roll of the second toward and from a corresponding roll of the first, a gear train interconnecting the rolls for rotation in unison, means for forcefully urging each roll in the second series into contact with a can body carried by the corresponding roll of the first series, and means at the free end of each roll of the first series for resisting the force thereby applied thereto.

4. A can body beading machine comprising a rotatable turret, means for rotating said turret, a plurality of pairs of beading rolls journalled in said turret and each comprising an outer roll supported at one end only and having a free end over which the can bodies may be passed and an inner roll mounted for outward radial movement into beading contact with a can body on the outer roll, means for forcefully moving the inner roll outwardly, and stationary means opposite the free ends of the outer rolls for resisting the force applied thereto by the inner roll.

5. A can body beading machine comprising a turret mounted for rotation on a horizontal axis, an outer series of beading mandrels, each having one end journalled in the turret and the other end free for the reception of a can body, a roller on the free end of each mandrel, a series of beading rolls carried by the turret in parallel relation to the mandrels, means for urging the beading rolls radially against can bodies on the mandrels to impress circumferential beads thereon,

and a stationary track positioned opposite to said rollers on the mandrels and resisting the force applied thereto by the beading rolls to prevent displacement of the free ends of the mandrels.

6. A can body beading machine comprising a turret mounted for rotation on a horizontal axis, a plurality of pairs of beading rolls journalled in said turret, each pair comprising one roll supported at one end only and having a free end over which can bodies may be passed and another roll mounted for radial movement into beading contact with a can body on the first roll, means for revolving the turret and for rotating the rolls, there being can body infeed and outfeed stations adjacent one portion of the path of revolution of the turret, a stationary arcuate track extending along another portion of said path and positioned adjacent the free ends of the first-mentioned rolls, and means for urging the second-mentioned rolls against the can bodies on the first-mentioned rolls to impress circumferential beads therein, said track serving to prevent displacement of the free ends of the rolls under the influence of the force applied thereto.

7. A can body beading machine comprising a turret mounted for revolution on a horizontal axis, a plurality of pairs of beading rolls journalled in said turret, each pair comprising an outer roll supported at one end only and having a free end over which the can bodies may be passed and an inner roll mounted for outward radial movement into beading contact with a can body on the outer roll, means for revolving the turret and the rolls, means adjacent the lower portion of the path of revolution of the rolls for delivering can bodies to and removing the same from the outer rolls, means for forcefully moving the inner rolls outwardly as the rolls traverse an upper portion of said path of revolution, and an arcuate track overhanging the free ends of the outer rolls during their movement along the last-mentioned portion of said path to resist the force applied thereto by the inner rolls.

8. A can body beading machine comprising a turret mounted for revolution on a horizontal axis, a plurality of pairs of beading rolls journalled in said turret, each pair comprising an outer roll supported at one end only and having a free end over which the can bodies may be passed and an inner roll mounted for outward radial movement into beading contact with a can body on the outer roll, said outer rolls each having an anti-friction roller journalled on its free end, means for revolving the turret and the rolls, means adjacent the lower portion of the path of revolution of the rolls for delivering can bodies to and removing the same from the outer rolls, means for forcefully moving the inner rolls outwardly as the rolls traverse an upper portion of said path of revolution, and an arcuate track overhanging the rollers on the free ends of the outer rolls during their movement along the last-mentioned portion of said path to resist the force applied thereto by the inner rolls.

9. A can beading machine comprising a supporting frame, a turret journalled in the frame for revolution on a horizontal axis, a plurality of horizontal can body receiving mandrels journalled

in the turret for revolution therewith, a plurality of horizontal, radially movable can beading rolls mounted inwardly of the mandrels for revolution therewith, infeed and outfeed means carried by said frame for delivering can bodies to and removing the same from said mandrels adjacent the lower portion of the path of revolution of the turret, an arcuate track carried by the frame and overhanging and contacting the free ends of the mandrels along an upper portion of said path of revolution, and means for forcefully moving the beading rolls radially outwardly into contact with can bodies on the mandrels as the latter move along the last-mentioned portion of said path, said track serving to prevent displacement of the mandrels under the influence of the force applied by the beading rolls.

10. A can body beading machine comprising a rotatable turret, a plurality of pairs of beading rolls journalled in the turret, each pair comprising an outer roll supported at one end and having a free end over which the can bodies may be passed and an inner roll supported at both ends and mounted for outward radial movement into beading contact with a can body on the outer roll, and means for moving the inner rolls outwardly and into such contact, the last-mentioned means comprising a bearing bracket for each end of each inner roll, a supporting platform for each bracket, compression spring means between each bracket and platform, a rack associated with each platform, and pinion means for reciprocating the racks, said compression spring means serving to permit the rolls to separate slightly as the side seam of the can body passes therebetween.

11. A can body beading machine comprising a rotatable turret, a plurality of pairs of beading rolls journalled in the turret, each comprising an outer roll supported at one end and having a free end over which the can bodies may be passed and an inner roll, and means for supporting the two ends of each inner roll and for moving the same outwardly into beading contact with a can body on the outer roll, each of said supporting and moving means comprising a hollow depending sleeve guided for radial movement in the turret and having rack teeth thereon, a platform carried by the sleeve pinion means in mesh with said teeth to reciprocate said sleeve and the platform, a bearing bracket, in which the roll is journalled, mounted above the platform and having a stem extending through said sleeve, and spring means between the platform and the bracket.

12. In a can body beading machine of the type wherein a plurality of beading rolls are mounted for radial movement into beading relation to can bodies supported upon mandrels carried in turn by a rotatable turret, improved means for supporting the beading rolls, comprising a platform adjacent each end of each roll having a rack sleeve mounted in the turret, a journal bracket having a stem slidably mounted for coaxial movement in each sleeve, compression spring means interposed between each platform and each bracket, and pinion means for reciprocating said rack sleeve.
